DESIGN FOR AN ASH RECEIVER OR THE LIKE

John Visser, Grand Rapids, Mich., assignor to F. L. Jacobs Company, Grand Rapids, Mich., a corporation of Michigan

Application April 28, 1939, Serial No. 84,650

Term of patent 7 years

To all whom it may concern:

Be it known that I, John Visser, a citizen of the United States, residing at Grand Rapids, in the county of Kent and State of Michigan, have invented a new, original, and ornamental Design for an Ash Receiver or the Like, of which the following is a specification, reference being had to the accompanying drawing, forming a part thereof, in which:

I claim:

The ornamental design for an ash receiver or the like, substantially as shown.

JOHN VISSER.
